UNITED STATES PATENT OFFICE.

FRANK H. ADAMS, OF CLEVELAND, OHIO.

REPEATING AND STOPPING ATTACHMENT FOR DISK PHONOGRAFS.

1,275,823.

Specification of Letters Patent. Patented Aug. 13, 1918.

Application filed March 23, 1914, Serial No. 826,489. Renewed October 5, 1917. Serial No. 195,000.

To all whom it may concern:

Be it known that I, FRANK H. ADAMS, a citizen of the United States, residing at Cleveland, in the county of Cuyahoga and State of Ohio, have invented a certain new and useful Improvement in Repeating and Stopping Attachments for Disk Phonographs, of which the following is a full, clear, and exact description.

10 The objects of this invention are, first, to enable a disk phonograph machine to automatically repeat the playing of records indefinitely; and second, when desired, to enable the machine to automatically stop itself when the playing of a record has been completed. The invention consists in the construction and combination of parts herein-after described and shown in the drawing, and definitely pointed out in the appended 20 claims.

In the drawing Figure 1 is a plan view of a disk phonograph machine equipped with the invention. Fig. 2 is a front elevation of so much of said machine as is necessary to show said invention. Fig. 3 is a bottom view of the track arm and connections. Fig. 4 is a side elevation thereof. Fig. 5 is a perspective view showing the track arm lifter, and a part of the track arm and its 25 adjuncts adjacent to said lifter. Fig. 6 is an end view of the turned down end of slide 12.

Referring to the parts by reference characters, 1 represents the sound box; 2 the sound box arm; and 3 the swinging tone arm, the same being a taper tube which is itself pivoted on a vertical axis 3^a. The sound box arm is pivoted to the free end of the taper tube on a horizontal axis indicated 40 by 2^a. 4 represents the turn table, and 5 a disk record, which does not differ from the ordinarily used disk records, except that it has one or more grooves 5^a formed in its upper surface and extending from the inner 45 end of the playing groove 5^b spirally toward the axis of the turn table. 6 represents the automatic brake lever which is pivoted on a vertical axis 6^a adjacent to the edge of the turn table. 7 represents the needle, carried 50 by the sound box. All of the above-mentioned parts are of the usual construction, except, as above stated, for the groove 5^a,

of which there may be more than one, if desired. The present invention is adjunctive to a disk phonograph having the above 55 mentioned parts.

10 represents the track bar which is pivoted to a bracket 11 fixed to the frame of the machine at one side of the turn table, the pivoting axis 11^a being substantially at right 60 angles to the axis 2^a about which the sound box tube turns. From its supporting pivot this bracket arm extends over the turn table toward the axis thereof just in front of the sound box and the needle carried thereby. 65 The rear edge of this track is curved more or less accurately about a center which is coincident with the axis 3^a upon which the taper tube turns.

On the under side of the arm 10 is an extension piece 12 which is in the form of a slide mounted and supported in guides 10^a. The end of this slide projects beyond the end of the track bar, and normally rests upon the smooth top surface of the disk like 75 base 13^a of the track bar lifter 13.

A clamp 14, which is secured to the tube 2 adjacent the sound box, is provided at its outer or front end with a downwardly extending arm 15 carrying at its lower end a friction roller 15^a for engagement with said track bar. The shape and disposition of the arm 14 is such that the roller 15^a will be over the track bar, but will not engage therewith when the track bar is in the horizontal 85 position it will occupy when its extension member 12 is resting as shown upon the disk 13^a. Under these conditions and with the parts constructed and arranged as stated, the ordinary operation of the phonograph 90 in playing the record will not be changed.

The track bar lifter 13 has in its bottom a hole which fits friction tight on the part of the spindle 4 which projects up through the record. The part of said lifter which extends above the base 13^a is preferably in the form of an inverted truncated cone, whose axis is coincident with the axis of the turn table. In the outer surface of this cone is a spiral groove 13^b which extends from 100 the base 13^a to the top thereof.

The sliding extension member 12 has near its free end a shoulder 12^a, which lies in the path of the needle 7 as said needle moves

toward the center of the turn table about the axis 3^a. There is also a shoulder 12^b carried by the slide 12 adjacent the outer edge of the disk record 5, and also projecting into the path of the needle as the taper tube swings about its axis 3^a away from the axis of the turn table.

The operation of the device thus far described will be as follows:

10 As stated, the parts are normally in the position shown by the full lines in Fig. 2, when a disk record is being played. When the needle 7 comes to the end of the playing groove, it will enter one of the grooves 5^a in 15 the disk record, and thereby will be carried rather quickly toward the axis of the turn table; and during this movement the needle will engage the shoulder 12^a with sufficient force to move the slide 12 inward so as to 20 move the inner end of said slide into the spiral groove 13^b of the track bar lifter. Then, as the lifter continues to revolve in unison with the turn table, the said spiral groove will gradually carry the end of said 25 slide 12 upward and thereby the track bar 10 will be lifted until it finally assumes the position shown by dotted lines in Fig. 2. As this track bar is lifted, it comes into contact with the friction wheel 15^a, and thereby the 30 sound box is swung up about its axis 2^a, lifting the needle clear of the record. The inclination of the track bar upon which the sound box is now supported will be such, as shown by dotted lines in Fig. 2, that gravity 35 will cause the sound box to roll down this track bar toward the outer edge of the disk, causing, of course, the taper tube 3 to swing laterally about its axis. As the sound box so travels, the needle 7 will be carried into 40 contact with the shoulder 12^b, and thereby the slide 12 will be moved outward. In so moving, it will be drawn free and clear of the lifter 13, and therefore, the track bar will drop to its former horizontal position. When 45 it does so drop, the sound box will be allowed to swing down, and the needle 7 will enter one of the playing grooves. Thereafter the playing of the record will proceed in the usual way. It will, of course, be understood 50 that it is desirable that the shoulder 12^b shall occupy a position such that when the needle 7 strikes and moves it, and when, as a result, the track bar drops, the needle will take its place in the playing groove of the record at 55 or very near the beginning thereof.

If disk records were always of one size, say 12 inches in diameter, and, if the playing grooves always began and ended at the same definite distance from the axis, the two 60 shoulders 12^a and 12^b could be immovable relative to the slide, and could be accurately placed thereon. As a matter of fact, however, there are two standard sizes of phonograph disks, to wit, twelve inch and ten inch. Likewise there is some variation in 65

the distance from the outer edge of each disk at which the playing groove begins, and there is still greater variation in the distance from the center on both sides of disks at which the playing grooves end.

The shoulders 12^a and 12^b, which are immovable parts of the slide 12, are located properly for use with the most common kind of twelve inch record; and for use with records which differ therefrom two devices are 75 movably fixed to the slide, and are so constructed that by their movement they may present shoulders for the needle to engage with, at various distances from the axis of the disk.

One of these devices is a lever 17, which is pivoted to the under side of the slide 12, its end which is farthest from the pivot 11^a, being provided with a plurality of steps or shoulders 17^a. This lever may be turned 85 upon its pivot so as to bring into the path of the needle that one of the shoulders which will be engaged by the needle at the desired point, viz. the point at which the track bar will drop so as to allow the needle to enter 90 the playing groove of the disk at the desired point. Since this lever is carried by the slide, the striking of the end of the lever by the needle will move the slide outward with the same results as when the needle struck 95 the shoulder 12^b.

Means for holding the lever 17 in any adjusted position may be provided. In fact, a simple segment latch is shown in the drawing. In the construction shown the 100 slide 12 is made of thin sheet metal; and it has projecting from its front side a segment shaped extension 18 having radiating grooves 18^a cut in its under surface, and the lever 17 has a punched up rib 17^b on its upper surface for engagement in these grooves. The metal of which the lever 17 is formed has enough spring to hold the rib in the proper groove with sufficient force to resist any 105 strain to move it which may be imparted by 110 the impact from the needle.

Another lever 19 is pivoted to the under side of the slide near the shoulder 12^a, but extending in a general direction outward therefrom,—that is away from the axis of the disk. It may be provided with plural shoulders 19^a, 19^b, so placed that this lever may be turned on its pivot to bring either of these shoulders into the path of the needle. If, for example, the playing groove on the 115 disk stops at a greater distance than common from the center of rotation, it is desirable to swing this lever 19 so as to bring one or the other of the shoulders 19^a, 19^b into the path of the needle. When the needle in its movement toward the center of the disk strikes whichever shoulder is in its path, it will move the slide 12 inward, and cause its end to enter the spiral groove of the lifter, with 120 the results which have been before explained. 130

It may be desirable to provide means by which the end of the slide 12, when it has once entered the spiral groove 13^b, shall be compelled to stay in said groove until the groove emerges from the top of the lifter. This may not be essential, and obviously is not essential to the invention in its broader aspects, but, as stated, it may be desirable. To that end the lower or lifting surface of the spiral groove is undercut, and the projecting end of the slide 12 has a turned down flange or toe 12^c, which enters the undercut part of said spiral groove. This construction may perhaps best be produced by winding a strip of metal 13^e spirally, as shown, around a central arbor 13^d, and connecting it at the top and bottom to said arbor. In that event, there should be at the top of the lifter an inwardly projecting surface 13^f, and the front edge of said down turned finger should be beveled as shown in Fig. 6. When the beveled edge of the finger comes in contact with said surface 13^f it will be lifted above the level of the top of the spiral groove; and there will also be provided another projection 13^g which will engage said finger when in this position, and push it off of the top of the lifter. This will insure that even if the needle shall not strike the shoulder 12^b or one of the other shoulders in its path carried by the slide with sufficient force to move the slide outward, nevertheless the slide will be pushed back and off of the lifter so that the track arm will certainly fall to the horizontal position and allow the needle to enter the playing groove. Before the slide is pushed off the lifter in the manner just stated, the sound box and needle will have been restored to starting position.

The way in which to stop the rotation of the turntable in a disk phonograph machine is to swing the automatic brake lever 6 outward,—that is, away from the turntable. Ordinarily this is done by hand, but the mechanism which has been heretofore described may be utilized to produce that result. For example, if the lever 17 is swung on its pivot so that it projects slightly under the forwardly projecting part of the lever 6 when the track arm is elevated or inclined in the manner previously described, that portion of lever 17, which is beneath the forwardly projecting part of lever 6 will engage the latter, moving the same slightly away from the turntable so that the spring of the brake device may throw the opposite end of the lever 6 or the brake shoe into engagement with the periphery of the turntable, and thus stop the rotation of the latter.

It is to be understood that any device carried by the sound box may be utilized for engaging the shoulder on the slide 12 to cause its movement; and that the utilization of the needle for this purpose is merely a matter of preference.

The word "phonograph" as used in the specification and claims is not intended to limit the invention to a machine sold under the name, phonograph, but includes any sound reproducing or so-called talking machine utilizing a disk record, of the general type herein shown and described.

Having described my invention, I claim:

1. In combination with a phonograph having a turntable adapted to receive a disk record, a driving spindle therefor, a tone arm and sound box, of a repeating attachment comprising a track arm pivoted at its outer end beyond the turntable and projecting inwardly toward the center of the latter, and means for inclining said track arm, comprising an elevating device having a grooved upright portion provided with a socket adapted to receive the upper end of the driving spindle and having a substantially flat base which is entirely above the surface of the record when the latter is in position on the turntable and is adapted to normally support the inner end of the track arm.

2. In combination with a phonograph having a turntable adapted to receive a disk record, a driving spindle therefor, a tone arm and sound box, of a repeating attachment comprising a track arm pivoted at its outer end beyond the turntable and projecting inwardly over and toward the center of the latter, and means for inclining the track arm comprising a device having a grooved upright portion, a substantially flat base which is above and rests on the surface of the record when the latter is in position on the turntable and a socket in said base adapted to receive the upper end of the driving spindle, and means carried by said track arm adapted to be shifted into engagement with the groove of said upright portion, said means normally supported by said base.

3. In combination with a phonograph having a turntable adapted to receive a disk record, a driving spindle for the turntable, a tone arm and a sound box provided with a needle, of a repeating attachment, comprising a single arm pivoted at its outer end beyond the periphery of the turntable and projecting inwardly and toward the center of the latter, said arm projecting over the turntable wholly to one side of the path of movement of the needle, an elevating device secured to the upper end of the driving spindle, means supported on the lower side of said arm adapted to be engaged by a part movable with the sound box to cause operative engagement between the track arm and the elevating device, said means projecting beyond that edge of the track arm which is adjacent the path of movement of the needle, and a roller mov-

able with the sound box adapted to engage the upper surface of said track arm when the inner end of the latter is elevated.

4. In combination with a phonograph having a turntable adapted to receive a disk record, a driving spindle for the turntable, a tone arm, a sound box, and a spring actuated brake adjacent the periphery of the turntable, of a repeating and stopping attachment, comprising a track arm pivoted at its outer end beyond the turntable and extending inwardly over and toward the center of the latter, means for elevating the inner end of said track arm so as to incline the same and cause the tone arm and sound box to be returned to starting position whereby the playing of the record will be repeated, and an adjustable device carried by said track arm and having a portion adapted to be shifted adjacent a part of said brake so that when the inner end of the track arm is elevated, said device will engage and shift said brake and permit the spring to throw the brake to braking position.

5. In combination with a phonograph having a turntable adapted to receive a disk record, a driving spindle for the turntable, a tone arm and a sound box, of a repeating attachment comprising a track arm pivoted at its outer end at the side of the turntable and extending inwardly over and toward the center of the turntable, and means for elevating the inner end of the track arm comprising a grooved elevating device adapted to be secured to the upper end of the driving spindle and having an upstanding portion in the shape of an inverted truncated cone.

- 40 6. In combination with a phonograph having a turntable adapted to receive a disk record, a driving spindle for the turntable, a tone arm a needle and a sound box, of a repeating attachment comprising a track bar pivoted at one side of the turn table, an automatic track bar lifter adapted to be readily connected with the spindle of the turn table above the record disk thereon, an arm adapted to be connected with the sound box so as to overhang said track bar and having a friction wheel mounted in its lower end, a movable member mounted on the track bar and having a shoulder which projects into the path of some device movable with the sound box, as for example the needle, whereby said member will be moved into engagement with the automatic track bar lifter, and means for automatically disengaging said slide from said track bar lifter.

7. In combination with a disk phonograph machine having a turntable adapted to receive a disk record, a driving spindle therefore, a tone arm, a sound box and needle, a track bar pivoted at one side of the turn

table of the machine and extending over said turn table and being supported at its inner end indirectly by said turn table, an arm movable with the sound box and overhanging said track bar, a track bar lifter located concentrically with respect to said turn table and rotating therewith, and a member movably mounted on the track bar and having a shoulder which lies in the path of some part which moves with the sound box whereby when said part engages the shoulder said member will be moved into operative engagement with said track bar lifter.

8. In combination with a disk phonograph machine having a turntable adapted to receive a disk record, a driving spindle for the turntable, a tone arm, a sound box and needle, a track bar pivoted at one side of the turn table of the machine and extending over said turn table and being supported at its inner end indirectly by said turn table, an arm movable with the sound box and overhanging said track bar, a track bar lifter located concentrically with respect to said turn table and rotating therewith, a member movably mounted on the track bar and having a shoulder which lies in the path of some part which moves with the sound box whereby when said part engages the shoulder said member will be moved into operative engagement with said track bar lifter, and means for automatically disengaging said member from the track bar lifter.

9. In combination with a disk phonograph machine having a turntable adapted to receive a disk record, a driving spindle for the turntable, a tone arm, a sound box and needle, a track bar pivoted at one side of the turn table of the machine and extending over said turn table and being supported at its inner end indirectly by said turn table, an arm movable with the sound box and overhanging said track bar, a track bar lifter located concentrically with respect to said turn table and rotating therewith, and an extension member movably mounted on the track bar and having a shoulder which lies in the path of some part which moves with the sound box whereby when said part engages the shoulder the extension member will be moved into operative engagement with said track bar lifter, and a second shoulder secured to said extension member at a point adjacent the periphery of the turn table and also lying in the path of a part which moves with the sound box.

10. In combination with a disk phonograph machine having a turntable adapted to receive a disk record, a driving spindle for the turntable, a tone arm, a sound box and needle, a track bar pivoted at one side of the turn table of the machine and extending over said turn table, a track bar

- lifter connected concentrically with said turn table and having a base member and an upright member which is circular in cross section and has in its surface a spiral groove 5 running from the base to the top thereof, a member movably mounted on the track bar and having a shoulder which projects into the path of some part connected with the sound box, as for example the needle, said 10 track bar being supported at its inner end by the base of the track bar lifter, and an arm movable with the sound box and extending over said track bar.
11. In combination with a disk phonograph machine having a turntable adapted to receive a disk record, a driving spindle for the turntable, a tone arm, a sound box and needle, a track bar pivoted on one side of the turn table of the machine and 15 extending over said turn table, a track bar lifter connected concentrically with said turn table and having a base member and a vertical member which is circular in cross section and has in its surface a spiral groove 20 running from the base to the top thereof, a member movably mounted on the track bar and having a shoulder which projects into the path of some part connected with the sound box, as for example the needle, and 25 an arm movable with the sound box and extending over said track bar, said member having also adjacent to the periphery of the turn table a second shoulder which lies in the path of some part connected with the 30 sound box, as for example said needle.
12. In combination with a disk phonograph machine having a turntable adapted to receive a disk record, a driving spindle for the turntable, a tone arm, a sound box and needle, a track bar lifter having in its 35 bottom a vertical hole adapted to fit friction tight on the spindle of the turn table and having a disk like base member and an upright member having in its surface a spiral groove 40 extending from the disk like base to the top thereof, a track bar pivoted at one side of the turn table of the machine and extending over said turn table, said track bar having a movable member normally resting 45 on the base of the lifter and adapted to be shifted into the groove of the lifter.
13. In combination with a disk phonograph machine having a turntable adapted to receive a disk record, a driving spindle 50 for the turntable, a tone arm, a sound box and needle, a track bar lifter having in its bottom a vertical hole adapted to fit friction tight on the spindle of the turn table and having a disk like base member and an up- 55 right member having in its surface a spiral groove 60 extending from the disk like base to the top thereof, a track bar pivoted at one side of the turn table of the machine and extending over said turn table, a slide 65 mounted upon said track bar and normally resting at its free end on the disk like base of the track bar lifter, said slide having a shoulder which projects into the path of the needle and is adapted to be engaged thereby, whereby the slide is moved outward and 70 its end pushed into said spiral groove, and said slide having also adjacent to the periphery of the turn table another shoulder which lies in the path of said needle and is adapted to be engaged thereby. 75
14. In combination with a disk phonograph machine having a turntable adapted to receive a disk record, a driving spindle for the turntable, a tone arm, a sound box and needle, a track bar lifter having in its 80 bottom a hole which fits upon the turn table spindle and has a disk like base and an up-standing member having in its surface a spiral groove which extends from said base to the top, a track bar pivoted at one side of the turn table of the machine and extending over said turn table, a member mounted upon said track bar and resting normally at its free end upon the disk like base of said track bar lifter and having a shoulder lying 85 in the path of the needle, and an arm movable with the sound box and overhanging said track bar and having a friction roller mounted in its lower end for engagement with said track bar. 90
15. In combination with a disk phonograph machine, having a turntable adapted to receive a disk record, a driving spindle for the turntable, a tone arm, a sound box and needle, a track bar lifter having in its 95 bottom a hole which fits upon the turn table spindle and has a disk like base and an up-standing member having in its surface a spiral groove which extends from said base to the top, a track bar pivoted at one side of the turn table of the machine and extending over said turn table, a slide mounted upon said track bar and resting normally at its free end upon the disk like base of said track bar lifter, an arm movable with the sound box and overhanging said track bar and having a friction roller mounted in its lower end for engagement with said track bar, and a movable device carried by said slide and having a shoulder which may be moved into the path of the needle, said movable device being connected with said slide at a point 100 near the inner end of the track bar. 105
16. In combination with a disk phonograph machine having a turntable adapted to receive a disk record, a driving spindle for the turntable, a tone arm, a sound box and needle, a track bar lifter having in its bottom a hole which fits friction tight upon the turn table spindle and has a disk like base 110 and an up-standing member having in its surface a spiral groove which extends from said base to the top, a track bar pivoted at one side of the turn table of the machine and extending over said turn table, a slide 115

6 mounted upon said track bar and resting normally at its free end upon the disk like base of said track bar lifter, an arm movable with the sound box and overhanging said 5 track bar and having a friction roller mounted in its lower end for engagement with said track bar, a movable device carried by said slide and having a shoulder which may be moved into the path of the needle, said movable 10 device being connected with said slide at a point near the inner end of the track bar, and a second device carried by said slide near the periphery of the turn table carrying a plurality of shoulders either of which may 15 be moved into the path of said needle.

17. In combination with a disk phonograph machine having a turntable adapted to receive a disk record, a driving spindle for the turntable, a tone arm, a sound box and 20 needle, a track bar lifter attached to the spindle of the turn table and having a disk like base member and an upstanding member having a spiral groove in its surface which extends from the base member to the 25 top thereof, a track bar pivoted to one side of the turn table and extending over the same, an arm movable with the sound box and extended therefrom over the track bar and having a friction roller in its lower end 30 for engagement with said track bar, a slide mounted upon said track bar and resting normally at its front end upon the disk like base of said lifter and having a shoulder which lies in the path of the needle, an automatic 35 brake lever adjacent the periphery of the turntable, a lever pivoted to the said slide near its outer end and adapted to be swung into a position adjacent the automatic brake lever, and a shoulder fixed to 40 said slide near its outer end in the path of said needle.

18. In a disk phonograph machine, having a rotatable turn table and an upwardly projecting spindle, a taper tube pivoted on 45 a vertical pivot to one side of said turn table, a sound box having an arm which is pivoted to said tube on a horizontal pivot, a playing needle carried by said sound box, and a disk record mounted on said turn 50 table and having in its top surface a groove which extends from the termination of the playing groove spirally toward the axis of the turn table, a track bar pivoted on a horizontal pivot to one side of the turn table 55 and extending over said turn table, an arm

fixed to the sound box and extending over said track bar and having at its lower end a friction roller for engagement with said track bar, a slide carried by said track bar and projecting beyond the inner end thereof, 60 a track bar lifter fixed concentrically to said turn table, and two shoulders carried by said slide lying in the path of the needle.

19. The combination in a repeating attachment for sound reproducing machines of 65 the disk record type having the usual reproducing mechanism, of a device for restoring the reproducing mechanism to a starting position with respect to the record, said device comprising a track bar adapted to extend 70 over the record, together with means for elevating the track bar to effect the restoration, a brake, and adjustable means associated with said track bar for at will selectively causing repeating of the record playing 75 when the said adjustable means is in certain positions, and causing actuation of the brake without repeating when in another position, the adjustable means being rendered effective by the elevation of the track bar. 80

20. In combination with a phonograph of the disk record type, having a turntable for rotating the record, and having a tone arm, and a sound box adapted to receive a reproducing needle; of a repeating attachment 85 comprising a track bar pivoted at the side of the turntable and adapted to extend inwardly over the latter, means at the center of the turntable to elevate the inner end of the track bar so as to cause the tone arm and 90 sound box to swing outwardly, and a device adjacent the outer end of the track bar projecting laterally beyond the track bar so as to be engaged by a part moving outwardly with the sound box alongside the track bar 95 when the inner end of the track bar is elevated, said device being adjustably mounted so that the laterally projecting portion may be positioned to stop the outward movement of the tone arm and sound box at certain 100 points between definite limits whereby the needle may be restored in the playing groove at the beginning thereof.

In testimony whereof, I hereunto affix my signature in the presence of two witnesses. 105

FRANK H. ADAMS.
